UNITED STATES PATENT OFFICE.

MILTON H. BALLARD, OF LYNN, MASSACHUSETTS, ASSIGNOR TO UNITED SHOE MACHINERY COMPANY, OF PATERSON, NEW JERSEY, A CORPORATION OF NEW JERSEY.

BUFFING DEVICE.

No. 927,926.

Specification of Letters Patent. Patented July 13, 1909.

Application filed August 19, 1904, Serial No. 221,392. Renewed October 14, 1907. Serial No. 897,352.

To all whom it may concern:

Be it known that I, MILTON H. BALLARD, a citizen of the United States, residing at Lynn, in the county of Essex and Commonwealth of Massachusetts, have invented certain Improvements in Buffing Devices, of which the following description, in connection with the accompanying drawings, is a specification, like reference characters on the drawings indicating like parts in the several figures.

This invention relates to buffing devices and is shown embodied in a heel scouring wheel.

15. Rotary buffing devices are in common use which are divided longitudinally of their axes into two sections hinged together and adapted to hold the two ends of a cover of abrading material between them.

20. The present invention is concerned more particularly with the improvement of devices of this class to the end that the cover may be quickly applied and securely held in working position.

25. The device herein shown and described comprises means for locking the sections in closed position, constructed to be mechanically brought into operation by the relative approaching movement of the sections in closing them upon the ends of the cover. The locking of the sections is thus automatically effected, and the necessity of manually actuating a locking device is avoided. In the present embodiment of the invention the

30. locking means is adapted to retain the sections in different closed positions. This not only permits different thicknesses of abrading material to be held in position upon the device, but also allows any looseness in the

35. grip of the sections upon the cover to be taken up, such as may be caused, for example, by the reaction of the work upon the cover. The arrangement shown is such that within a certain range of relative movement 40 of the sections, lying at the end of their closing movement, the locking means is automatically effected to hold the sections from separating from whatever position within said range to which they may be forced. If

45. desired, the arrangement may be such that the reaction of the work upon the device will tend to close the sections so that any loose-

ness in the grip of the sections upon the abrading material will be automatically taken up in the use of the device.

55. Other features of the invention, including details of construction and arrangements of parts, will be hereinafter described and defined in the claims.

In the drawings, which illustrate a heel 60 scouring wheel constituting one embodiment of the invention;—Figure 1 is a side elevation of the wheel showing the sections in open position; Fig. 2 is a view in side elevation, partly in section, of a portion of the 65 wheel showing the parts at an initial stage of the approaching movement of the sections; Figs. 3, 4 and 5 are views similar to Fig. 2, showing successive positions of the parts; Fig. 6 is a transverse sectional view 70 on the line $\alpha-\alpha$ of Fig. 1; Fig. 7 is a view in side elevation of the position of the wheel illustrated in Fig. 6; Fig. 8 is a view in perspective of a portion of the locking mechanism illustrated in the preceding views.

75. Referring to the drawings, the reference numerals 2 and 3 indicate the two sections of a heel scouring wheel which are hinged together at 4 and covered with a leather strip 5 having a layer of felt 6 secured thereto. As is well-known in the use of a device of this form, a cover 1 of abrading material is wrapped about the periphery of the wheel, the two ends of the cover being clamped between the two sections.

80. The movable section 2 is provided at its free end with an arm 7 which, as shown, is made integrally therewith. The section 3 which is fixed upon a supporting shaft is provided at the end adjacent to the arm 7 with a recess to receive the arm 7, said recess being formed by the walls 8 and 9. Mounted in the walls 8 and 9 in position to lie above the arm 7 in the closed position of the parts is a rotatable member 10 which has 85 engagement with the arm 7. The member 10 is provided intermediate its ends with a segmental shaped portion 11. The portion 11 is so shaped that its periphery is of a gradually increasing radius as shown in any 90 one of Figs. 2 to 5 inclusive, and the member 10 is so mounted that the rounded face of the portion 11 has contact with the outer face 12 of the arm 7 when the sections are 95 100

brought together, and thus locks the sections in closed position. It will be apparent from the drawings that by bringing different points upon the portion 11 into contact with the arm 7 the sections may be held from separating movement in different relative positions.

I preferably provide means by which the segment 11 is moved automatically to hold the sections 2, 3 from separating from the closed positions which they assume. This comprises means tending to rotate the member 10 to bring a point of increased radius on the round face of segment 11 in contact with the arm 7. A convenient arrangement is a flat, coiled spring 13 having one end inserted in an orifice 14 in the end portion 15 of member 10 and its other end inserted in an orifice in wall 9, as shown in Fig. 7. This spring tends to move the segment 11 into the position shown in Fig. 5. The wall 9 may be provided with a cavity 16 to receive the spring 13, and the end portion 15 of the member 10 may be reduced as shown.

To enable the parts above described to be mechanically given locking position when the sections are moved into closed position, I arrange said parts so that the approaching movement of the sections sets and releases the spring-actuated locking member 10. For this purpose the parts may be so arranged that the end 7 in the approaching movement of the sections engages the inner end of segment 11, as shown in Fig. 2, and turns the member 10 about its axis against the resistance of spring 13 until the segment is brought into the position shown in Fig. 3. In this position of segment 11 the arm 7 is free to pass by the member 10. When said arm is moved by the flat face of segment 11 the member 10 is released and is permitted to be turned by the spring 13 to bring the rounded face of the segment 11 into locking position, as illustrated in Fig. 4. It will be observed that the oscillation of the member 10 which takes place in the locking operation, illustrated by the drawings, is effected mechanically in the closing movement of the sections, so that all that is required to lock the sections is to move them together.

To permit unlocking of the sections 2, 3 I preferably make the member 10 laterally movable to carry the segment 11 out of engagement with the arm 7. As shown, I have provided the member 10 with a slot or cut-away portion 18, through which the end of the arm 7 may pass when said arm is disengaged from the segment 11. The slot 18 is so formed as to permit the outward movement of the arm 7 at any one of the locking positions which the segment 11 may assume. The member 10 is normally held in position so that segment 11 is in the path of the arm 7 by a metal strip 19 attached at 20 to the wall of the cavity 16 and serving by its

elasticity to hold the member 10 to the right in Fig. 6. The strip 19 may be formed if desired to cover the cavity 16, as shown in Fig. 7. To limit the lateral movement of the member 10 in the unlocking operation 70 said member may be provided with a head 21. It will be understood that movement of the member 10 in the reverse direction is limited in the structure shown by the coiled spring 13. The walls 8, 9 are provided with 75 cavities to receive the head 21 and segment 11, respectively, in the lateral movement of the member 10.

In the use of the polishing or scouring roll shown on the drawings, I prefer to 80 mount the roll so as to be rotated in a left-handed direction, viewing Fig. 1. With such an arrangement, it will be observed that the action of the abrasive material on the object operated upon will tend to force 85 more closely together the roll sections. The sections being automatically locked from separating movement at all points in the range of relative movement permitted said sections in their closed position, it will be seen that 90 any excessive space between the clamping faces will be automatically taken up in the rotation of the roll and the grip of the roll sections upon the flexible material maintained.

Having described my invention, what I claim as new and desire to secure by Letters Patent of the United States is:—

1. A rotary device for sustaining a cover of abrading material having a plurality of 100 relatively movable cover-supporting sections arranged to grip between them the two ends of the cover and mechanism for locking said sections in closed position arranged to be mechanically actuated by the relative movement 105 of the sections, and constructed to permit the sections to be locked in different relative positions.

2. A rotary device for sustaining a cover of abrading material, having two relatively 110 movable sections arranged to receive between them the two ends of the cover and forming in their closed position a cover-supporting surface, mechanism for locking said sections arranged to be brought into operation by 115 the relative approaching movement of the sections, and constructed for locking the sections in different relative positions, and means for actuating said locking mechanism.

3. A rotary device for sustaining a cover 120 of abrading material having a plurality of relatively movable cover-supporting sections arranged to grip between them the two ends of the cover, locking mechanism for holding said sections from separating movement constructed to become effective at any point 125 within a predetermined range of relative movement of the sections, and means for actuating said locking mechanism.

4. A rotary device for sustaining a cover 130

of abrading material having two relatively movable sections arranged to receive between them the two ends of the cover and forming in their closed position a cover-supporting surface, a member rigidly connected to one of said sections, a pivotally supported locking device carried by the other of said sections and arranged to engage said member in its pivotal movement to lock the sections together, and means for moving said device into locking position.

5. A rotary device for sustaining a cover of abrading material, having two relatively movable sections arranged to receive between them the two ends of the cover and forming in their closed position a cover-supporting surface, a locking member pivotally mounted upon one of said sections, and means carried by the other of said sections 15 arranged to be engaged by an acting face of said locking member to lock the sections together, said face having portions at different distances from the axis of said member to permit the locking of the sections in different 20 relative positions.

6. A rotary device for sustaining a cover of abrading material having two relatively movable sections arranged to receive between them the two ends of the cover and forming 25 in their closed position a cover-supporting surface, a member mounted in stationary position upon one of said sections, a rotatable locking device carried by the other of said sections, and arranged to engage said 30 member in its movement to lock the sections together, and means to automatically turn said device into locking position upon the

movement of said sections into closed position.

7. A rotary device for sustaining a cover of abrading material having two relatively movable sections arranged to receive between them the two ends of the cover and forming in their closed position a cover-supporting surface, a member mounted in stationary position upon one of said sections, an oscillatory device carried by the other section and arranged in its oscillation to engage said member to lock the sections together, and means to automatically oscillate 50 said device in the relative approaching movement of the sections.

8. A rotary device for sustaining a cover of abrading material having two relatively movable sections arranged to receive between them the two ends of a cover and forming in their closed position a cover-supporting surface, an arm carried by one of said sections, a locking member carried by the other section and having means normally 55 in the path of said arm arranged to engage the arm to lock the sections together, said locking member being movable laterally of the sections to move said means out of the path of the arm and permit separation of 60 the sections.

In testimony whereof I have signed my name to this specification in the presence of two subscribing witnesses.

MILTON H. BALLARD.
